UNITED STATES PATENT OFFICE.

WILLIAM L. HUDSON, OF SYRACUSE, NEW YORK.

RADIOCONDENSER.

Application filed August 18, 1925. Serial No. 50,921.

This invention relates to a radio condenser involving the use of opposed sets of plates which are relatively adjustable for varying the capacity as may be required for selective tuning of the receiving instrument with sending instruments of local or distant stations.

In radio condensers of this type commonly used, the opposed sets of condenser plates are relatively adjustable by means of a suitable indexing device graduated to correspond to various wave velocities of different broadcasting stations but in many instances where there are only slight variations in wave velocities from the different sending stations or where the receiving waves are relatively weak it is extremely difficult, if not impractical, to selectively tune the receiving instrument with the sending stations and in order to overcome this difficulty it is customary to provide what is commonly known as a "vernier condenser" or adjustment which permits a sharper or closer tuning of the receiving instrument with the station desired.

The main object of this invention is to provide in one and the same condenser means for selectively tuning the receiving instrument with not only the widely varying wave velocities but also with the slightly varying wave velocities or intensities of local or distant broadcasting stations.

In other words, I have sought to provide a simple form of variable condenser in which the opposed plates have at least two relative adjustments, one for approximate selective tuning and the other for a closer selective regulation of the approximate tuning whereby the receiving instrument may be easily, quickly and accurately tuned to any one of a number of slightly varying wave velocities of as many stations without interference from any other station.

Another object is to reduce to a minimum the liability of back lash or lost motion in the primary adjusting means and thereby to increase the efficiency of the capacity regulation of the condenser.

Another object is to simplify the construction of the plate supporting elements and at the same time to enable the plates of each set to be more firmly and positively held in the desired spaced relation and thereby to establish a more uniform and symmetrical air dielectric between the plates.

A still further object is to reduce to a minimum the liability of inductance or cur-

rent leakage to and from the condenser plates and external conductors.

One of the specific objects is to provide simple and efficient means for adjusting one set of condenser plates relatively to the other set after the other set has been adjusted to bring the condenser into approximate tune with the desired sending station.

Other objects and uses relating to specific parts of the invention will be brought out in the following description:

In the drawings:

Figure 1 is a perspective view of my improved condenser and the adjusting devices for both sets of plates.

Figure 2 is an enlarged detailed sectional view taken on line 2—2, Figure 1, the upper portion of the apparatus including the condenser plates being omitted.

Figure 3 is an enlarged transverse vertical sectional view taken on line 3—3, Figure 1.

As illustrated, this device comprises a supporting standard —1— having a substantially flat base —2— adapted to be secured to any available support, not necessary to herein illustrate or describe, except that the device is to be properly associated with other parts of a radio receiving set.

The standard —1— is provided with an L-shaped top —3— in which is supported a bar —4— of insulating material such as "bakelite" which rests upon the lower ledge of the part —3— and is secured to the back thereof by suitable screw —5—.

The upper L-shaped portion —3— of the standard —1— is provided with a forwardly projecting hub —6— in which is journaled a rotary shaft —7—, the latter being extended through an opening in the bar —4— and beyond the rear face thereof for receiving a pinion —8— tight thereon, said pinion having its hub abutting against the rear face of the bar —4— to hold the shaft against forward axial movement.

A collar —9— is secured to the intermediate portion of the shaft —7— to abut against the hub —6— and thereby to hold the shaft and pinion against axial movement rearwardly, the front end of the shaft being provided with the usual hand-operated dial —10— secured thereto and movable around a suitable stationary plate —11—, both of which are shown by dotted lines in Figure 3.

The opposite ends of the bar —4— extend upwardly some distance above the pinion —8— to form a front rest for a horizontally

movable sliding bar —12— directly over the pinion —8— said bar —12— being partially held in place against rearward displacement by an upright guide loop —13—

5 which is secured to one end of the bar —4— some distance to one side of the pinion —5— for guiding the adjacent end of the bar —12— in its longitudinal movement.

A horizontal guide loop —14— is secured 10 to the other end of the bar —4— adjacent to the lower edge of the bar —12— for additionally supporting the latter in its longitudinal movement. The lower end of the bar —12— is provided with a toothed rack 15 —12'— meshing with the uppermost teeth of the pinion —8— and through which reciprocatory motion is transmitted from the pinion to the bar as the pinion is rotated in reverse directions by means of the dial 20 —10—.

The upper ends of the upstanding portions as —4'— and —4''— of the bar —4— are provided with rearwardly projecting blocks —15— secured thereto directly over 25 and in spaced relation to the upper edge of the sliding bar —12— for receiving and supporting one end of a pair of U-shaped spring shims —16— having their other ends spring pressed against the adjacent upper edge of 30 the slide bar —12— for pressing said bar downwardly and yieldingly holding the teeth of the rack —12'— in engagement with the teeth of the pinion —8— thereby reducing to a minimum any back lash or lost 35 motion of the slide bar —12— which is preferably made of insulating material such as "bakelite."

An upright post —17— is rigidly secured 40 at its lower end to the rear face of the slide bar —12— to extend upwardly some distance therefrom and carries at its upper end a cross bar —18— of insulating material as "bakelite" and upon this cross bar is securely fastened the outer arms of a W-shaped 45 metallic plate —19— having laterally projecting loops —20— in vertically spaced relation.

These loops are provided with a series 50 of vertically aligned relatively narrow slots —21— for receiving a corresponding number of condenser plates —22— constituting one set on the condenser.

Suitable metallic pins —23— are passed 55 through the slots —21— in the loops —20— and through the registering openings in the plates —22— for rigidly holding said plates in the slots against lateral displacement with the outer edges of the plates resting firmly against the intermediate portions of the 60 conductor plate —19—.

The slots —21— in the loops —20— of the plate —19— are accurately spaced uniformly the same width as the thickness of the 65 plates —22— so as to firmly hold said plates

in fixed correspondingly spaced relation and parallel with each other, the pins —23— and central portion of the plate —19— serving to firmly hold the condenser plates —22— against lateral movement relatively to the 70 cross bar —18— which, in turn, is rigidly secured to the post —17— and thereby holds the plates —22— in fixed relation to the slide bar —12— to move therewith.

An additional upright post —17'— is 75 pivoted intermediate its ends at —24— to the block —15— on the upper end of the post —4'— to swing lengthwise of and in a plane parallel with the slide bar —12—.

The lower end of the post —17'— is preferably angular or square in cross section and extends through an elongated slot —14'— in the horizontal guide loop —14—, the slot —14'— being of slightly greater width lengthwise of the bar —12— than the 85 adjacent portion of the post —17'— to permit a limited rocking movement of said post about the axis of its pivot —24— for a purpose presently described.

The upper end of the post —17'— is rigidly secured by means of a clamp —25— to an insulating block —18'— similar to the block —18—. Rigidly secured to the block —18'— is a W-shaped metallic plate —19'— which is similar to the plate —19— in that it is provided with loops —20'— having slots —21'— for receiving a series or set of condenser plates —22'— which are rigidly held in operative position and in parallel spaced relation in their respective slots by 95 pins —23'— similar to the pins —23—.

It will be observed however that the plate —19'— contains one more of the slots —21'— than the plate —19— and that they are arranged in alignment with the spaces 105 between the plates —22— so that when the plates are brought into overlapping relation they will be in parallel spaced relation with air dielectrics between them.

The plates of both sets are of substantially 110 the same form and size and when adjusted for use are disposed in substantially the same horizontal plane parallel with and above the slide bar —2—.

The lower and upper edges of the plates 115 are substantially straight and parallel while their adjacent edges are slightly beveled from their longitudinal centers toward their lower and upper edges so that the inner edge of each plate has what might be 120 termed a "flat taper" to permit the capacity of the condenser to be adjusted to a closer degree than would be possible if the inner edges of the plates were straight and parallel.

Suitable means is provided for rocking the post —17'— about the axis of the pivot 125 —24— for effecting a corresponding movement of the plates —22'— relatively to the plates —22— said means consisting in this 130

instance of a rock shaft —26— journaled in a suitable bearing —27— on the lower bar —4— and having its rear end provided with an eccentric cam —28— adapted to engage the outer upright edge of the lower end of the post —17— for rocking said post against the action of a retracting spring —29— which is interposed between the lower end of the post —17'— and a stud —30— projecting rearwardly from the bar —4— as shown in Figure 1.

The front end of the shaft is provided with a pointer —31— and a handle —32— by which latter the shaft may be turned to move the pointer around a dial plate —33—, and at the same time to rotate the eccentric —28— against the post —17—.

It is now evident that the coiled spring —29— serves to yieldingly hold the lower end of the post —17— against the periphery of the eccentric —28— and that if, by rotating the shaft —26— to bring the lower point of the eccentric against the post the latter will be actuated by the spring —29— to move the upper end of the post and parts carried thereby toward the plates —22— and that if the shaft is rotated to bring the high point of the cam into engagement with the post against the action of the spring —29— the upper end of the post —17'— and parts carried thereby will be moved away from the plate —22—.

The difference in length of the short diameter and long diameter of the eccentric is relatively small and therefore the maximum movement of the plates —22— toward and from the plates —22— will be correspondingly small and will be accomplished through practically one-half revolution of the shaft —26— thus permitting a very close adjustment of the plates —22— after the plates —22— have been adjusted to an approximate tuning position for any selected sending station.

For example, if two or more local or distant sending stations are using only slightly different wave velocities and it is desired to selectively tune the receiving station equipped with my improved condenser with any one of these sending stations the shaft —7— and its pinion —8— will first be rotated to move the slide bar —12— and plates —22— carried thereby into approximately the proper tuning relation with the plates —22— after which the shaft —26— and its eccentric —28— may be operated to adjust the post —17— and plates —22'— carried thereby in one direction or the other as may be necessary or until the receiving instrument is properly tuned with the selected sending station, it being understood that the last named adjustment is relatively slight and more easily controlled than the first-named adjustment and provides in a single condenser the means for selectively tuning

any receiving instrument with different sending stations having weak or slightly different wave velocities, in addition to its regular function of tuning with sending stations having widely varying wave velocities.

Furthermore by spacing the plate supporting posts —17— and —17'— relatively wide distances apart and mounting them upon the opposite ends of an insulating bar —4— and also in using the insulating bar —12— reduces to a minimum the liability of electrical interference from external sources when the plates are tuned with some particular sending station.

It will be noted that one set of plates as —22— is adjustable rectilinearly relatively to the other set of plates as —22'— and that the latter has an independent adjustment through an arc of a circle about the axis of the pivot —24— toward and from the plates —22— for additionally varying the effective capacity of the condenser after the primary adjustment has been made.

The post —17— cooperates with the loop —13— to limit the movement of the bar —12— and plates —22— carried thereby in one direction, said bar being provided with a stop pin —12'— cooperating with the post —17'— to limit the movement of the bar —12— in the opposite direction.

What I claim is:

1. A variable condenser comprising opposed sets of plates having their adjacent edges tapered toward their longitudinal centers, one set being adjustable rectilinearly, and means for adjusting the other set in an arc of a circle across the path of the first-named set.

2. A variable condenser comprising opposed sets of plates, means including a slide for adjusting one set through a relatively long range, and separate means for adjusting the other set about an axis through a relatively shorter range.

3. A variable condenser comprising opposed sets of plates, means including a sliding bar for supporting one set of plates, and means including a pivoted post for supporting the other set of plates rotatably about the axis of the pivot.

4. A variable condenser comprising opposed sets of plates, means including a sliding bar for supporting one set of plates, means including a rack and pinion for reciprocating the sliding bar and means for moving the other set of plates transversely of the movement of the bar.

5. A variable condenser comprising opposed sets of plates, means including a sliding bar for supporting one set of plates, a guide for said bar, and resilient shims on the guide engaging the bar for yieldingly and frictionally holding the latter against lost motion in the guide.

6. A variable condenser of the character described comprising a slide, a post secured to the slide, a plate holder mounted on the post and having parallel loops provided with parallel transverse slots, plates seated in said slots, and pins passing through the loops and through registering apertures in the plates. 30
7. A variable condenser of the character described comprising a W-shaped metallic plate support having parallel loops provided with parallel transverse slots, condenser plates seated in said slots, pin passing through the loops and through registering apertures in the plates, and an insulating block secured to and between the opposite arms of said plate support. 35
8. A variable condenser comprising opposed sets of plates, means including a rack and pinion for adjusting one set of plates rectilinearly relatively to the other set, and means including a cam for adjusting the other set of plates relatively to the first-named set. 40
9. A variable condenser of the character described comprising opposed sets of plates, means including a sliding bar for moving one set of plates rectilinearly relatively to the other set, and means including a pivoted
- post for moving the other set of plates relatively to the first-named set. 45
10. A variable condenser of the character described comprising opposed sets of plates, means including a sliding bar for supporting one set of plates, means including a rack and pinion for reciprocating said bar, means including a pivoted post for supporting the other set of plates, and means including a rotary cam for adjusting the pivoted post about the axis of its pivot. 50
11. In a variable condenser of the character described, a set of condenser plates, supporting means for said plates including a slide for moving the plates endwise, a guide for the slide, resilient means on the guide for engaging the slide and frictionally holding it in its adjusted position, and a rack and a pinion for reciprocating the slide. 55
12. In a variable condenser of the character described, a set of condenser plates, a supporting block for said plates, a supporting post for the block pivoted to swing in the direction of length of the blades, and means including an eccentric engaging the post for rocking the post upon its pivot. 60

In witness whereof I have hereunto set my hand this 12th day of August, 1925.

WILLIAM L. HUDSON.
